UNITED STATES PATENT OFFICE.

WILLIAM H. CLAUSEN, OF MELROSE, MASSACHUSETTS.

GAME APPARATUS.

1,161,846.

Specification of Letters Patent. Patented Nov. 30, 1915.

Application filed March 16, 1915. Serial No. 14,743.

To all whom it may concern:

Be it known that I, WILLIAM H. CLAUSEN, of Melrose, in the county of Middlesex and State of Massachusetts, a citizen of the 5 United States, have invented a new and useful Improvement in Game Apparatus, of which the following is a specification.

My invention is intended to provide a 10 table apparatus for the playing of a game in which the moves of a game of baseball are imitated.

It will be understood by reference to the 15 drawings in which the apparatus for playing the game is shown in its preferred and most elaborate form, although certain of the details of construction may be omitted if a less elaborate form of apparatus is desired, score cards being substituted therefor.

Figure 1 is a plan view of such preferred 20 form of board on which the game is played. Fig. 2 is a section on line 2—2 of Fig. 1, and Fig. 3 is a plan of the ball with which the game is played.

A is the board proper which is preferably 25 square in shape, though its shape is immaterial. It has about it a rim α .

B is the diamond on and about which the 30 game is played and which comprises a central portion b preferably square. From this square arises sloping walls b^1 which as shown arise slightly above the general level 35 of the board. At each corner of the diamond, as I call the whole part B, are arranged squares 1, 2, 3 and 4, which represent the four bases and at 5 and 6 are arranged 40 squares on which each side may stack counters to represent the number of outs and runs in an inning. At x^1 — x^9 are a series of squares to represent innings, within which squares the runs of one side may be counted 45 by counters, and on the opposite side of the board are corresponding squares y^1 — y^9 in which the runs of the other side may be counted by counters, making the total score by innings of the game.

The board is slotted as at C and D, and 50 within each slot is mounted a rod c and d on which slide counters c^1 and d^1 , these counters being preferably five in number and on these are counted the balls and strikes.

The game is played by means of a poly-

hedron ball E (see Fig. 3) on the various faces of which are marked characters to indicate the plays. These faces are some of them e hexagonal and some of them e^1 pentagonal, each having its own value in connection with the character placed upon it. In Fig. 1 one side of the ball is shown and in Fig. 3 the opposite side of the ball is shown. Preferably the ball has thirty-two faces of 60 which twenty are hexagons and twelve are pentagons.

In playing the game the ball is allowed to roll down one of the sloping faces of the diamond, and by reason of its size and the 65 impetus which it gets it perhaps rises a little on the opposite side, but gradually settles down somewhere upon the flat portion b of the diamond, and the play is read from the top face of the ball. For example, in Fig. 1 70 the play is B in a hexagon, this standing for one ball. In Fig. 3 the character S being the top character and the face being hexagon, the score is a strike.

Various faces on the ball preferably count 75 as follows: F in a hexagon is "foul"; F in a pentagon, preferably with a circle around it, means "foul out"; H in either a hexagon or a pentagon is a "hit out"; S, whether in a hexagon or pentagon is a "strike"; and similarly B is a "ball." The character 1 means a one base hit; 2 a two base hit; 3 a three base hit; and R a home run.

In playing the game colored counters or 85 chips may be conveniently used, the red counters indicating the players and runs of one side, the blue counters the players and runs of the other side, and white counters to indicate the outs. The general rules of 90 playing the game of baseball are observed so far as they apply.

In practice, one player sits opposite the other with the board turned so that the squares x^1 — x^9 and y^1 — y^9 are each in front of a player, the counters c^1 and d^1 being on 95 the sides of the board. The counters c^1 and d^1 are used to count both strikes and balls as will be described.

The player sitting with the squares x^1 — x^9 in front of him has his innings first, and 100 having say the red side, places a red counter on the square marked 4. The other player

sitting opposite him rolls the ball down either sloping face of the diamond and if it turns up as shown in Fig. 1 with B on its upper face, that counts one ball, and the 5 player having his innings pushes up one of the counters e^1 on the rod e . His opponent thereupon rolls the ball a second time and if it turns up as in Fig. 3, S, this being a strike and to the advantage of the man who is 10 "pitching," the pitcher pushes up one of the counters d^1 . The pitcher then rolls the ball again, and perhaps a number 3 turns up. The one having his innings moves his counter from the home base 4 around to base 3 15 and places another counter on 4 to represent the next striker. The ball then rolled by the pitcher perhaps turns up at R and the striker makes a home run, moving his man from 4 around the four bases and driving in 20 the man already on 3. This gives him two runs for which he places counters in the compartment 5. He places another counter on 4 to represent the next striker and the ball is rolled turning up at H representing a 25 "hit out" and a white counter is put in the compartment 6. This being perhaps repeated twice more and three players being out, the side is out, whereupon he takes the ball and becomes pitcher and his opponent, 30 the former pitcher, puts up a blue counter on square 2 to represent the striker and the new pitcher rolls the ball to determine what the next move will be. The counters in 5 representing the runs of the innings are 35 moved to the compartment x^1 , etc. representing the score.

Variations of and additions to the game 40 may be conveniently made. For example, by the use of the hexagon and pentagon faces e, e^1 of the ball E the successful or unsuccessful stealing of a base may be indicated, the player whose innings it is notifying that he intends to steal a base by perhaps placing a second counter on top of the 45 counter which is already on one of the three bases or in some other way. In such case, if a hexagon comes up for example with the letter H on it, the man who steals may be moved to the next base, this representing a 50 sacrifice hit. On the other hand, if the H on a pentagon turns up after this notice to steal, the man stealing is out as well as the striker, this being a double play. Where the letter S in a pentagon turns up, the man 55 who is to steal is out, the strike having presumably having been caught by the catcher, and the ball being thrown to the base which the runner is trying to steal. If a B in a pentagon turns up it indicates that the man 60 stealing is safe at his next base. F on a pentagon indicates that the foul is out. In each case the counters are moved as the play requires.

These various suggestions indicate how

this apparatus may be used and, while they 65 have been satisfactorily worked out, are merely suggestions which may be varied to suit the desire of the players. The whole, however, affords an amusing reproduction 70 of the moves of a baseball game with all the elements which such a game affords, and the essentials are the diamond preferably with its sloping sides and means, preferably a ball like that shown, whereby the necessary moves may be indicated. 75

I have called the part B the "diamond" using the ordinary language of baseball, but its outline is immaterial. The flat portion serves as the final resting place of the ball and the sloping sides as an incline down 80 which the ball rolls. It is best angular in outline as the angles of the sloping sides to each other may be used to vary the paths of the ball which sometimes will cross the flat portion and run up the opposite slope 85 and fall back again into the flat portion.

What I claim as my invention is:—

1. A game apparatus comprising a diamond having a flat portion and sloping sides surrounding said flat portion, and a poly- 90 hedron ball having symbols on its faces.

2. A baseball game apparatus comprising a board having a diamond shaped recess provided with sloping sides and stations indicating the bases, and a polyhedral ball 95 having symbols on its faces indicating various plays of a baseball game.

3. A baseball game apparatus comprising a board having a diamond shaped recess provided with sloping sides and stations indicating the bases, in combination with means 100 to indicate the various plays of a baseball game.

4. A baseball game apparatus comprising a board having thereon a baseball diamond 105 provided with sloping sides, stations indicating bases, one located at each corner of the diamond, and separate means for scoring balls and strikes, said means comprising rods suitably mounted and counters slidably 110 mounted thereon, and a polyhedral ball having symbols thereon indicating the various plays.

5. A baseball game apparatus comprising a board having thereon a baseball diamond 115 shaped recess provided with sloping sides, stations indicating bases, one located at each corner of the diamond, separate means for scoring balls and strikes, and a polyhedral ball having symbols thereon indicating 120 the various plays, some of said faces being pentagonal and some of said faces being hexagonal.

6. A game apparatus comprising a dia- 125 mond having a flat portion and sloping sides, and a polyhedral ball having symbols on its faces, its faces being of various shapes.

7. A baseball game apparatus comprising a board having a diamond shaped recess with sloping sides located thereon, stations at the corners of said diamond indicating bases, two rods, counters slidably mounted thereon to indicate strikes and balls, and means whereby runs and outs in each in-

ning may be separately scored, in combination with a polyhedral ball, the faces thereof being of different shapes, said faces bearing symbols representing the various plays of the game. 10

WILLIAM H. CLAUSEN.
